CLAIM

The ornamental design for a reeled garbage bag holder, as shown and described.

DESCRIPTION

FIG. 1 is a reduced perspective view of the reeled garbage bag holder showing my new design;

FIG. 2 is a top plan view thereof;

FIG. 3 is a front elevational view thereof;

FIG. 4 is a bottom plan view thereof;

FIG. 5 is a sectional view taken along the line 5—5 of FIG. 3;

FIG. 6 is a side elevational view taken from the right of FIG. 3;

FIG. 7 is a side elevational view taken from the left of FIG. 3.
